COMBINED INSTRUMENT CASE AND FLIGHT DESK

Jon W. Hauser, 200 W. Main St., St. Charles, Ill.

Filed Dec. 24, 1964, Ser. No. 83,154

Term of patent 14 years

(Cl. D87—5)

FIG. 1 is a perspective view of a combined instrument case and flight desk embodying my new design;

FIG. 2 is an exploded perspective view thereof, showing the instrument case partially open; and

FIG. 3 is a detail sectional view thereof, taken on line 3—3 of FIG. 1.

I claim:

The ornamental design for a combined instrument case and flight desk, substantially as shown.
